UNITED STATES PATENT OFFICE.

JOHN M. HERMAN, OF NEWARK, NEW JERSEY.

DESIGN FOR A LAMP-BODY.

SPECIFICATION forming part of Design No. 29,535, dated October 25, 1898.

Application filed October 15, 1896. Serial No. 609,028. Term of patent 7 years.

To all whom it may concern:

Be it known that I, JOHN M. HERMAN, a citizen of the United States, residing at Newark, in the county of Essex and State of New Jersey, have invented and produced a new and original Design for a Bicycle-Lamp Body; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

10 In the accompanying drawings, Figure 1 is a side elevation of the body of a bicycle-lamp of my novel design, and Figs. 2 and 3 are respectively central, vertical, and horizontal sections of the same.

15 The leading feature of the design resides in a lamp-body the globular center part of which is ornamented with a diagonal rib lying in a plane crossing the vertical axial line of the dome and said center part, as shown in 20 the accompanying illustration.

25

In said drawings, *a* indicates the globular center part of the lamp-body, and *b* the dome, the center axis of which is disposed in the line of the vertical axis of the said center part above the same.

e is a cylindrical-shaped part axially in line with said dome beneath said center part, and *c* is the lens at the front side of said center part.

g indicates a bead or rib equatorially extending around and ornamenting the circumference of said globular center part and lying in a plane which diagonally crosses the vertical axial line of the said dome, center part, and cylindrically-shaped part.

What I claim as new is—

The design for a lamp-body, substantially as herein shown and described.

In testimony that I claim the foregoing I have hereunto set my hand this 21st day of 45 September, 1896.

JOHN M. HERMAN.

Witnesses:

CHARLES H. PELL,
C. B. PITNEY.
